FIRING MECHANISM

Wilfred E. Thibodeau, Cleveland, Ohio, and
Gregory J. Kessenich, Madison, Wis.

Application January 24, 1941, Serial No. 375,798

7 Claims. (Cl. 102—79)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to projectiles in general and in particular to small or medium arms explosive or incendiary projectiles. In these types of projectiles the use of known fuse structures is prohibitive because of size, complexity, cost and time of manufacture and assembly. The relatively large quantities of the smaller arms produced require a firing mechanism which is simple, inexpensive and easy of manufacture and assembly.

These objects are attained in the projectile of the invention which comprises essentially a carrier member for a firing pin which is designed for foreshortening on impact. The carrier may or may not be of springy material and may or may not have a safety barrier member to prevent premature foreshortening.

It is an object of the invention therefore to produce a projectile having a carrier for a firing element designed to foreshorten on impact.

It is another object of the invention to produce a projectile having a carrier for a firing element designed to foreshorten on impact and a safety barrier for said carrier to prevent foreshortening prior to firing.

It is a further object of the invention to produce a projectile having a tubular carrier member for a firing element, said tubular carrier having an open work structure to permit foreshortening thereof on impact.

To these and other ends, the invention consists in the construction, arrangement and combination of elements described hereinafter and pointed out in the claims forming a part of this specification.

A practical embodiment of the invention is illustrated in the accompanying drawings wherein:

Figure 1 is a section in elevation of the forward portion of a projectile;

Figure 2 is a similar view showing a modification;

Figures 3 to 9 are elevational views of modifications of the carrier member;

Figure 10 is an elevational view partly in section of the centrifugal barrier member;

Figure 11 is a perspective view of a modification of the centrifugal barrier member;

Figure 12 is an elevational view partly in section of a modification of the centrifugal barrier member, and

Figure 13 is a section in elevation of portions of the forward part of a projectile showing the invention employed as an all-ways fuse.

Referring to the drawings by characters of reference, there is shown in Figure 1 a projectile body 1 with an axial bore 2 in the nose thereof, and a slightly larger bore 3 rearward thereof and forming a step 4. A central cavity 5 communicating with the forward bores 2 and 3 contains a main explosive charge 6. Threadedly engaged in bore 3 at its inner terminus is a ring member 7 forming a flash passage and a seat for a primer 8.

Surrounding primer 8 and seated on a shoulder 9 thereof is a tubular member 10, the central longitudinal portion of which consists of spaced helical convolutions. In the forward portion of the tube 10 is snugly fitted a firing pin 11 having a head 12 engaging the end portion of tube 10, the diameter of said head being equal to or smaller than that of the forward bore 2.

Surrounding tube 10 and snugly fitted in the larger bore 3 is another tubular member 13 having inwardly struck portions 14 engaging the spaces between the convolutions of tube 10. These struck portions serve as an effective barrier to shortening of the tube 10 and consequent motion of the firing pin 11 in ordinary handling. On firing, however, the struck portions will recede from between the convolutions under the urging of centrifugal force and leave the tube 10 in condition for foreshortening if impact should occur. For short firing distances as in airplane combat the projectile will remain in armed condition, but on abatement of the speed of rotation it will return to safe condition and render the projectile non-explosive on falling to earth.

It will be noted that the detonating units are readily assembled separately from the projectile and simply inserted therein, in this case from the rear of the projectile.

In Figure 2 is shown a modification of the invention wherein the firing unit is inserted from the nose end of the projectile. Here the collapsible tube 15 has an extension throughout the length of the projectile to house the main charge 16. Thus, the entire explosive unit may be separately assembled for insertion into the projectile. The tube 15 is shown as held in the projectile by a rear plug 17 but this portion may be an integral part of the shell. Forward of the projectile, the firing assembly is held by threaded engagement of the outer tube 18 with the projectile.

The firing members shown are easily adapted

for use in the base as well as in the nose of a projectile.

In Figure 3 is shown a carrier member similar to tube 10 of Figure 1 which consists of a tube 31 having helical slots 32 cut therein.

In Figure 4 is shown a carrier generally similar to that of Figure 3 but with helical slots 33 of smaller pitch and having the helical portion 34 of less wall thickness than the unslotted portions of the cylinder 35. Either or both the pitch and the thickness of the helical portion may be varied within wide limits.

In Figure 5 is shown a carrier having separate peripheral slots 36, approximately semicircular in extent and in staggered relation along the length of the carrier 37. These slots may be greater or less than semicircular in peripheral extent and may be of any desired width.

In Figure 6 is shown a carrier 38 having slots 39 generally similar to those of Figure 5 but of a width of the order of the radius of the carrier.

In Figure 7 is shown a carrier 40 generally similar to that shown in Figure 6 but having wedge-shaped slots 41 instead of semicircular.

In Figure 8 is shown a carrier 42 having straight longitudinal slots 43.

In Figure 9 is shown a carrier 44 having a series of perforations 45 in the central portion thereof. This type as well as that of Figure 8 may be used where heavy impacts will be encountered, as in firing against armor plate.

The examples of carriers shown are not intended to be exhaustive but serve to represent the sort of changes which may be made in the carrier to design it for different modes of service. In each case the central weakened portion may have thinner walls than the ends of the tube to augment buckling on impact.

In Figure 10 is shown a separate view of a centrifugal barrier member 46 similar to barrier 13 of Figure 1. The inwardly struck portions are shown at 47.

In Figure 11 is shown another type of locking member which consists of a bar 48 having arms 49 bent inward for engagement in the openings of the carrier member.

Figure 12 shows another type of barrier member in which the tongues 20 are struck in the direction of the elements of the cylindrical carrier 19.

In Figure 13 is shown the essential portions of an all-ways fuse. A domed head 21 of the firing pin is nested at the apex of a cone-shaped depression 22 in the under side of a nose piece 23 of a projectile. Fitted around the shank 24 of the firing pin is a collapsible tube 25 and in the other end of the tube is fitted a primer 26. The primer 26 has a frusto-conical bottom piece 27 nesting in a flared opening 28 leading to a flash hole 29. A centrifugal bolt 30 keeps the helical tube 25 from that full compression which is necessary to establish contact between the firing pin and primer. A set back safety is threaded through bolt 30 and held there by a spring. On impact at glancing angles the firing pin head 21 will move on the cone surface 22 thus compressing the tube 25 and, the centrifugal bolt 30 having been re-

5 moved in flight, the pin will contact the primer. The centrifugal barriers of Figures 1 and 2 may also be used in this type of fuse, and the centrifugal bolt of Figure 13 may be used in the fuses of Figures 1 and 2.

In the known type of all-ways fuse the firing pin is carried in one of two telescoping members which are held apart by a centrifugal bolt. In the modification of the present invention the pin carrier has been simplified by reducing it to a single member. It is also safer because even without the centrifugal bolt the tube 25 can be designed to permit firing only on heavy impact.

We claim:

1. For use in a projectile an impact firing system comprising a striker member and a tubular holder therefor, said holder having an open work structure consisting of helical slots whereby the holder may be foreshortened on impact, and helical centrifugally removable barrier means extending into said slots to prevent foreshortening prior to firing.

2. For use in a projectile, an impact firing system comprising a striker member and a tubular holder therefor having an open work structure whereby the holder may be foreshortened on impact, and centrifugally removable barrier means to prevent said foreshortening prior to firing, said barrier means comprising a member outside the tubular member and having tongue portions bent into the openings of the open work structure.

3. A firing system for projectiles as in claim 2 wherein said barrier means comprises a sleeve surrounding said tubular member and having struck portions bent inward to engage the openings of the open work structure.

4. A firing system for projectiles as in claim 2 wherein said barrier means comprises a sleeve surrounding said tubular member and having peripheral struck portions bent inward to engage the openings of the open work structure.

5. A firing system for projectiles as in claim 2 wherein said barrier means comprises a sleeve surrounding said tubular member and having longitudinal struck portions bent inward to engage the openings of the open work structure.

6. For use in a projectile, an impact firing system comprising a tubular member and a striker member received in the end thereof and held against progress inward thereof, said tubular member having a central, helical structure of spaced convolutions to permit of foreshortening on impact and consequent motion of the striker, a sleeve surrounding said tubular member, said sleeve having struck portions bent into the spaces between adjacent convolutions of the helical portion of the tubular member to prevent full compression of the same prior to firing but to diverge therefrom under centrifugal force after firing.

7. In a projectile, a fuse, comprising a tube, helical slots in said tube, a helical barrier member inserted in said slots and means in the projectile to receive said helical member out of the line of the elements of said tube.
